FLEXIBLE DIATHERMY ELECTRODE

Fritz A. Anderson, Milton, and Sherrill K. Rasmussen,
Milton Junction, Wis., assignors to The Burdick Corporation,
Milton, Wis., a corporation of Delaware

Application April 7, 1954, Serial No. 29,888

Term of patent 14 years

(Cl. D26—1)

Fig. 1 is a top plan view of a flexible diathermy electrode embodying our new design;

Fig. 2 is a side elevational view of the electrode shown in Fig. 1;

Fig. 3 is a bottom plan view thereof; and

Fig. 4 is an end elevational view of the electrode, the other end being substantially identical thereto.

We claim:

The ornamental design for a flexible diathermy electrode, substantially as shown and described.
